UNITED STATES PATENT OFFICE.

WILLIAM H. SCHELM, OF EAST PEORIA, ILLINOIS.

DESIGN FOR A VEHICLE-BODY.

54,687.

Specification for Design.

Patented Mar. 9, 1920.

Application filed March 30, 1918. Serial No. 225,823. Term of patent 14 years.

To all whom it may concern:

Be it known that I, WILLIAM H. SCHELM, citizen of the United States, residing at East Peoria, in the county of Tazewell and State of Illinois, have invented a certain new, original, and ornamental Design for a Vehicle-Body, of which the following is a specification, reference being had to the accompanying drawing, forming part thereof.

Fig. 2 is a similar view showing the body from the opposite end.

I claim:

The ornamental design for a vehicle body, as shown.

In testimony whereof I affix my signature, in presence of two witnesses.

WILLIAM H. SCHELM.
